METAL SLIDE FASTENERS AND METHOD OF MAKING SAME

Ambrose J. McNamara, White Plains, N.Y., assignor to
Irving Constant, Esq., New York, N.Y.
Filed Mar. 3, 1959, Ser. No. 796,955
10 Claims. (Cl. 24—205.16)

The present invention relates to metal slide fasteners and method of making same. More particularly, the present invention relates to a method of making metal slide fasteners in which the metal slide fastener elements are provided with a finish after the elements have been attached to the tapes of the slide fastener.

In the making of metal slide fasteners, it is often desirable to provide the metal slide fastener elements with a finish, such as a protective coating, a coloring, and/or a lubricant coating. Such finishes are often applied by an electrolytic process, such as electro-plating, or anodizing. Heretofore, the metal slide fastener elements have been made from wire which was provided with the finish prior to forming the elements, or a string of the elements was provided with the finish prior to cutting the elements apart. However, such elements had bare, unfinished spots where the elements had been cut and formed from the wire or string. Also, the slide fastener elements have been completely formed and then provided with the finish prior to attaching the elements to the slide fastener tapes. However, this requires the handling of the individual elements which complicates the process of attaching the elements to the slide fastener tapes.

It is desirable to apply the finish to the slide fastener elements after the elements have been attached to the slide fastener tapes so as to provide the finish over the entire surface of the elements without the necessity of handling the individual elements. However, when the finish is applied by an electrolytic process, there is a problem of making good electrical contact with the elements since the elements are mounted in spaced relation on the slide fastener tapes which are of an electrically non-conducting material. Attempts have been made to overcome this problem by weaving into, or otherwise intimately uniting with, a slide fastener tape a metal conductor to provide electrical contact along all of the slide fastener elements attached to the tape. However, the incorporation of metal conductors in the slide fastener tape impairs the flexibility of the slide fastener. Furthermore, when the finish is applied to the slide fastener elements after the elements have been attached to the slide fastener tapes, the tapes are brought into contact with the treating chemicals, which may damage the tapes.

It is an object of the present invention to provide a method of making metal slide fasteners.

It is another object of the present invention to provide a method of making metal slide fasteners in which the slide fastener elements are provided with a finish.

It is still another object of the present invention to provide a method of making metal slide fasteners in which the slide fastener elements are provided with a finish after the elements have been attached to the slide fastener tape.

It is a further object of the present invention to provide a method of making metal slide fasteners in which the slide fastener elements are electrolytically provided with a finish after the elements have been attached to the slide fastener tape.

It is a still further object of the present invention to provide a method of making metal slide fasteners in which the slide fastener elements are provided with a finish after the elements have been attached to the slide fastener tape without damaging the tape.

2

Other objects will appear hereinafter.

For the purpose of illustrating the invention there is shown in the drawings forms which are presently preferred; it being understood, however, that this invention is not limited to the precise arrangements and instrumentalities shown.

FIGURE 1 is a front elevational view of a portion of a typical metal slide fastener.

FIGURE 2 is an elevational view, partly sectioned, of a portion of a typical slide fastener stringer made in accordance with the method of the present invention.

FIGURE 3 is a sectional view taken on line 3—3 of FIGURE 2.

FIGURE 4 is a view illustrating the first step of the method of the present invention.

FIGURE 5 is a sectional view taken along line 5—5 of FIGURE 4.

FIGURE 6 is a view illustrating the next step of the method of the present invention.

FIGURE 7 is a view illustrating still the next step of the method of the present invention.

FIGURE 8 is a view illustrating the final step of the method of the present invention.

FIGURE 9 is a sectional view through a slide fastener stringer showing a modification of the method of the present invention.

Referring initially to FIGURE 1, there is shown a typical metal slide fastener, generally designated as 10. Slide fastener 10 comprises a pair of tapes 12 and 12a of an electrically non-conducting material, such as a woven cloth tape. Each of the tapes 12 and 12a has a welt 14 and 14a respectively along its inner edge. A plurality of metal slide fastener elements 16 are secured in longitudinally spaced relation to each of the welts 14 and 14a of the tapes 12 and 12a. A slider 18 is movable along the slide fastener elements 16 to couple and uncouple the elements 16 of the tapes 12 and 12a. Slider 18 has a pull tab 20 by which the slider can be moved along the slide fastener elements 16. Each of the tapes 12 and 12a with the slide fastener elements 16 secured thereto is referred to as a "stringer."

The method of the present invention relates to a method of making a stringer. FIGURE 4 illustrates the first step in the method of the present invention.

Referring to FIGURE 4, a continuous length tape 12 is moved longitudinally in the direction of arrow 22. As the tape 12 moves along, a continuous length strip 24 of an electrically conductive metal foil, such as aluminum, is placed along the welt 14 of the tape 12. If desired, the metal foil strip 24 may have a paper or plastic lining on its side which contacts the welt 14. However, the total thickness of the metal foil strip 24, with or without a paper or plastic lining, is approximately between .001 inch to .003 inch. As shown, the metal foil strip 24 passes around a wheel 26 which places the strip 24 against the welt 14 of tape 12. The slide fastener elements 16 are then placed on the welt 14 of tape 12 and over the metal foil strip 24. As shown in FIGURE 5, each of the metal slide fastener elements 16 is substantially Y-shaped, with the arms 16a of the element 16 receiving the welt 14 of tape 12 and the metal foil strip 24 therebetween.

The arms 16a of slide fastener element 16 are spread apart a distance sufficient to permit the arms 16a to be placed around the welt 14 and the metal foil strip 24. However, the arms 16a of the slide fastener element 16 have sufficient contact with the welt 14 and the metal foil strip 24 to hold the slide fastener element 16 substantially perpendicular to the longitudinal axis of the welt 14 and to make good electrical contact with the metal foil strip 24.

FIGURE 6 shows the next step of the method of the

present invention, which comprises the process of applying a finish to the metal slide fastener elements 16. As shown, the process for applying a finish to the slide fastener elements 16 comprises an electrolytic process for electro-plating or anodizing the slide fastener elements 16. The tape 12 with the metal foil strip 24 and slide fastener elements 16 thereon is moved in the direction of arrow 28 through a vessel or tank 30. The vessel 30 is filled with an electrolyte, and a cathode 32 of the material to be electroplated onto the slide fastener elements 16 is within the electrolyte. The cathode 32 is connected to the negative side of a source of electrical energy, not shown. The metal foil strip 24 is connected through a sliding or rolling contact 34 to the positive side of the source of electrical energy. Thus, the metal foil strip 24 and the metal slide fastener elements 16, which are in electrical contact with the metal foil strip 24, form an anode. Thus, with the source of electrical energy turned on, as the tape 12 is moved through the vessel 30, the metal slide fastener elements 16 are electro-plated with the material of the cathode 32. The speed of the tape 12 through the vessel 30 will determine the thickness of the finish applied to the slide fastener elements 16.

FIGURE 7 shows the next step of the method of the present invention, which comprises securing the slide fastener elements 16 tightly to the tape 12. After the finish has been applied to the slide fastener elements 16, the arms 16a of the slide fastener 16 are pressed together to clamp them tightly around the welt 14. As shown, this is accomplished by passing the tape 12 and the slide fastener elements 16 between a pair of rams 36. The rams 36 are forced toward each other to engage the arms 16a of the slide fastener element 16, and force the arms 16a together to clamp the arms 16a around the welt 14 of tape 12. However, in place of the rams 36, the arms 16a of the slide fastener element 16 can be forced together by any other means well known in the art, such as a pair of rollers or a pair of camming surfaces. As the arms 16a of the slide fastener elements 16 are tightly clamped around the welt 14 of tape 12, the side edges of the arms 16a bite into and cut the metal foil strip 24.

FIGURE 8 shows the final step of the method of the present invention. As previously stated, when the slide fastener elements 16 are clamped tightly around the welt 14 of the tape 12, the metal foil strip 24 is cut into small segments by the side edges of the arms 16a of the slide fastener elements 16. The final step of the method of the present invention is the removal of the segments of the metal foil strip 24 from between the slide fastener elements 16. The tape 12 having the slide fastener elements 16 tightly clamped thereto is passed across a revolving brush 38. The bristles of the brush 38 engage the segments 24a of the metal foil strip 24 which are between the slide fastener elements 16, and remove the segments 24a from the welt 14 of tape 12. In place of brush 38, any other suitable means may be used for removing the segments 24a of the metal foil strip 24 from the welt 14 of tape 12.

FIGURES 2 and 3 show a portion of the completed slide fastener stringer. The metal slide fastener elements 16 are tightly secured in longitudinally spaced relation along the welt 14 of the tape 12. Each of the metal slide fastener elements has a coating 40 of the desired finish over its entire surface. A small segment 24b of the metal foil strip 24 is clamped between each of the slide fastener elements 16 and the welt 14 of the tape 12. The tape 12 can now be cut into desired lengths which are assembled with a slider 18 to form the completed slide fastener 10. Since the portions of the metal foil strip 24 which were between the slide fastener elements 16 were removed, the flexibility of the slide fastener 10 is not impaired.

Referring to FIGURE 9 there is shown a modification of the method of the present invention. A substantially U-shaped strip 42 of metal foil is placed around the welt

14 of tape 12 with the arms 44 and 46 of the metal foil strip 42 extending across the side of the tape 12 for the entire width of the tape 12. The arm 46 of the metal foil strip 42 is longer than the arm 44, and the end 46a of the arm 46 is folded across the outer end of tape 12 and across the end of the arm 44 of the metal foil strip 42. Thus, the metal foil strip 42 completely encloses the tape 12 and welt 14.

The slide fastener elements 16 are then placed on the welt 14 and around the base of the metal foil strip 42 in the same manner as described with regard to FIGURE 4. The slide fastener elements 16 are then provided with a finish in the same manner as previously described with regard to FIGURE 6. Since the tape 12 is completely enclosed in the metal foil strip 42, as the tape 12 passes through the tank 30, the tape 12 is not exposed to the electrolyte within the tank 30. Thus, the tape 12 cannot be damaged by the chemicals in the electrolyte. Also, if the finishing process is one to apply a color to the slide fastener elements 16, the color of the tape 12 will not be affected by the color being applied to the slide fastener elements 16. Therefore, the tape 12 can be one color while a different color is being applied to the slide fastener elements 16. After the finish has been applied to the slide fastener elements 16, the elements 16 are clamped tightly around the welt 14 which also causes the metal foil strip 42 to be cut along each side of the slide fastener elements 16. The metal foil strip 42 is then removed from the tape 12 and from the portions of the welt 14 between the slide fastener elements 16.

Although the method of the present invention is shown and described as comprising separate individual steps, the steps of the method of the present invention can be carried out as a single continuous operation. Also, although the method of the present invention is shown and described with regard to making a slide fastener having a particular type and shape slide fastener element, it is to be understood that the method of the present invention is also applicable to making metal slide fasteners having any of the well known type and shape slide fastener elements.

The present invention may be embodied in other specific forms without departing from the spirit or essential attributes thereof and, accordingly, reference should be made to the appended claims, rather than to the foregoing specification as indicating the scope of the invention.

I claim:

1. A method of making a metal slide fastener having a tape with a plurality of slide fastener elements secured in longitudinally spaced relation to an edge of the tape which comprises placing a strip of metal foil around the edge of the tape, placing the slide fastener elements in longitudinally spaced relation around the edge of the tape and in contact with said metal foil strip so that portions of said strip will be exposed, applying a finish to said slide fastener elements, then clamping said slide fastener elements tightly to said tape, and removing the exposed portions of said metal foil strip.

2. A method of making a metal slide fastener having a tape with a plurality of slide fastener elements secured in longitudinally spaced relation to an edge of the tape which comprises placing a strip of metal foil along the edge of the tape, placing the slide fastener elements in longitudinally spaced relation around the edge of the tape and around and in contact with at least a portion of said metal foil strip, applying a finish to said slide fastener elements, then clamping said slide fastener elements tightly to said tape so as to cause said slide fastener elements to cut through said metal foil strip, and removing the exposed portions of said metal foil strip.

3. A method of making a metal slide fastener having a tape with a plurality of slide fastener elements secured in longitudinally spaced relation to an edge of the tape which comprises placing a strip of metal foil along the edge of the tape, placing the slide fastener elements in

longitudinally spaced relation around the edge of the tape and around and in contact with at least a portion of said metal foil strip, electrolytically applying a finish to said slide fastener elements, then clamping said slide fastener elements tightly to said tape so as to cause said slide fastener elements to cut through said metal foil strip, and removing the exposed portions of said metal foil strip.

4. A method in accordance with claim 3 in which the finish is applied to the slide fastener elements by passing the tape having the metal foil strip and slide fastener elements thereon through a vessel containing an electrolyte and a cathode within the electrolyte with the slide fastener elements passing through the electrolyte, and connecting the metal foil strip in an electrical circuit with a source of electrical energy and the cathode.

5. A method of making a metal slide fastener having a tape with a plurality of slide fastener elements secured in longitudinally spaced relation to an edge of the tape which comprises enclosing said tape within a strip of metal foil, placing the slide fastener elements in longitudinally spaced relation around the edge of the tape and in contact with said metal foil strip, applying a finish to said slide fastener elements, then clamping said slide fastener elements tightly to said tape, and removing the exposed portion of said metal foil strip.

6. A method of making a metal slide fastener having a tape with a plurality of slide fastener elements secured in longitudinally spaced relation to an edge of the tape which comprises enclosing said tape within a strip of metal foil, placing the slide fastener elements in longitudinally spaced relation around the edge of the tape and around and in contact with at least a portion of said metal foil strip, applying a finish to said slide fastener elements, then clamping said slide fastener elements tightly to said tape so as to cause said slide fastener elements to cut through said metal foil strip, and removing the exposed portions of said metal foil strip.

7. A method of making a metal slide fastener having a tape with a plurality of slide fastener elements secured in longitudinally spaced relation to an edge of the tape 40

which comprises enclosing said tape within a strip of metal foil, placing the slide fastener elements in longitudinally spaced relation around the edge of the tape and around and in contact with at least a portion of said metal foil strip, electrolytically applying a finish to said slide fastener elements, then clamping said slide fastener elements tightly to said tape so as to cause said slide fastener elements to cut through said metal foil strip, and removing the exposed portions of said metal foil strip.

5 10. A method in accordance with claim 7 in which the finish is applied to the slide fastener elements by passing the tape having the metal foil strip and slide fastener elements thereon through a vessel containing an electrolyte and a cathode within the electrolyte with the slide fastener elements passing through the electrolyte, and connecting the metal foil strip in an electrical circuit with a source of electrical energy and the cathode.

15 15. A metal slide fastener stringer comprising a slide fastener tape, a plurality of metal slide fastener elements secured in longitudinally spaced relation to one edge of said tape, and a separate piece of metal foil clamped between each of said slide fastener elements and said tape.

20 25. 10. A metal slide fastener stringer comprising a slide fastener tape, a plurality of metal slide fastener elements secured in longitudinally spaced relation around one edge of said tape, and a separate substantially U-shaped piece of metal foil extending around the edge of said tape beneath each of said slide fastener elements and clamped between said elements and said tape.
